UNITED STATES PATENT OFFICE

114,673

DESIGN FOR A COCKTAIL SHAKER

Andrew Cravaritis, New York, N. Y., assignor to National Silver Deposit Ware Co., Inc., New York, N. Y., a corporation of New York

Application February 25, 1939, Serial No. 83,205

Term of patent 7 years

To all whom it may concern:

Be it known that I, Andrew Cravaritis, a citizen of the United States and resident of New York city, in the county of Bronx and State of New York, have invented a new, original, and ornamental Design for a Cocktail Shaker, of which the following is a specification, reference being had to the accompanying drawing, forming part thereof.

I claim:

The ornamental design for a cocktail shaker, substantially as shown.

ANDREW CRAVARITIS.
